DESIGN FOR A STOCKING

Samuel I. Burd and Martin M. Burd,
Philadelphia, Pa.

Application June 28, 1940, Serial No. 93,303

Term of patent 3½ years

To all whom it may concern:

Be it known that we, Samuel I. Burd and Martin M. Burd, both citizens of the United States, residing at Philadelphia, county of Philadelphia and State of Pennsylvania, have invented a new, original, and ornamental Design for Stockings, of which the following is a specification, reference being had to the accompanying drawing, forming a part thereof.

The characteristic feature of our design resides in the top portion of the stocking as shown.

We claim:

The ornamental design for a stocking, as shown and described.

SAMUEL I. BURD.
